UNITED STATES PATENT OFFICE.

HENRY CAVE, OF HARTFORD, CONNECTICUT, ASSIGNOR TO BUXTON, INCORPORATED.
OF SPRINGFIELD, MASSACHUSETTS, A CORPORATION OF MASSACHUSETTS.

KEY CASE.

Application filed February 7, 1924. Serial No. 691,169.

This invention relates to improvements in key cases and, more particularly, to improvements in the manner of mounting the key retaining clips or hooks.

5 The invention has for one object the provision of means which will facilitate the selection, from a group of key retaining devices, of that device which carries the desired key.

More particularly, it is an object of the invention to provide, on each key retaining hook, an extension adjacent the pivotal axis thereof, which extension can be used as a finger piece to turn the hook on its axis and thereby separate it and its key from the remaining hooks and keys.

To enable this object to be still more effectually carried out, identification marks may be associated with each of said extensions so that one can locate the desired key by the 20 number, or other mark, associated with the extension of the retaining hook therefor.

The invention is applicable to key cases of the swivel and non-swivel types but, in carrying out the invention with the swivel type 25 of key case, certain other advantages, entirely unrelated to the ease of selection of the keys, are obtained.

For example, the heads of the hooks are usually swivelled as well as pivoted in a 30 transversely-slotted, hollow, cylindrical member and the hook passes through this slot and is free to swing therein. Clearance between the hook and the walls of the slot is essential and, since the heads of the hooks 35 usually fit loosely in said member, the hooks frequently have considerable side play. By utilizing the described hook extension, which also enters into the slot and usually on the opposite side of the pivotal axis from the hook, the side play of the hooks is very materially 40 reduced and restricted within closer limits.

It is therefore another object of this invention to provide on each hook an extension which enters said slot but which need not 45 necessarily pass out of and beyond the slot.

According to this feature of the invention, each hook has a double bearing in its slot, preferably, as near as may be, at diametrical- 50 ally opposite points, which arrangement affords a more ample and effective guiding of the hook in its swinging movement than is ordinarily afforded.

It has heretofore been proposed to make the swivel head for the key retaining hooks 55 by bending the upper portion of the shank

into substantially the form of a circle, the axis of which is substantially parallel with the shank of the hook. When such a head is used, trouble is sometimes experienced in disposing of the end of the wire which, unless 60 bent inwardly from the circumference of the circular head, may catch and bind in the hollow cylindrical member. Such end, according to this invention, may be disposed of by bending it upwardly beyond the swivel head 65 to form the described extension, thereby not only eliminating a source of trouble but also accomplishing another desirable advantage.

Other objects and advantages will appear in the following description and in the illustrative embodiment of the invention in the accompanying drawings, in which:—

Fig. 1 is a front elevational view of an open key case showing one embodiment of the invention;

Fig. 2 is an enlarged fragmentary cross sectional view thereof;

Fig. 3 is a fragmentary rear elevational view of the key case when closed;

Fig. 4 is a view, taken similarly to Fig. 2, 80 showing a modification of the invention;

Fig. 5 is a fragmentary front elevational view of the construction shown in Fig. 4;

Fig. 6 is a view, taken similarly to Fig. 2, 85 showing another embodiment of the invention; and

Figs. 7 and 8 are enlarged fragmentary elevational and top plan views showing the construction of the upper end of one of the key retaining hooks.

Referring to these drawings and particularly to Figs. 1, 2 and 3; the key case chosen to illustrate the invention is of a well known type, comprising a series of key retaining devices 10, such as snap hooks, pivotally supported from a metal plate 11, which is suitably attached, as by rivets 12, to the central portion 13 of a folder of flexible material. The end portions 14 of this folder are foldable in overlapping relation over the central 100 portion 13 and may be secured by interengagable fastening devices 15. The invention may equally well be embodied in other types of key cases, if desired.

According to one feature of the invention, 105 each hook 10 is provided with an extension 16, which may be used as a lever or finger piece to cause the hooks to swing about their pivotal axis, which, in the example illustrated, is that of a cylindrical member 17, formed as 110

an integral part of plate 11. The member 17 is usually provided with a plurality of transverse slots 18 to permit the hooks 10 to swing in the desired arc-like paths into and out of the key case and these slots also receive the extensions 16. The latter extend through and beyond the slots and are located on the opposite side of the pivotal axis from the hooks. The particular way in which the hooks 10 are pivoted is immaterial so far as this feature of the invention is concerned.

In carrying out this feature of the invention, it is necessary to provide clearance for the members 16 and when the latter are located as shown in Fig. 2, it may be necessary to extend the slots 18 in plate 11 to enable the extensions to swing through the desired arc of travel, which is usually 180 degrees. The central portion 13 of the folder is also slotted near its upper end, as at 20, for the same purpose and, to prevent the cut edges of the folder from fraying, a finishing plate 21 may be provided on the back of portion 13, which plate may be held in place by the rivets 12, described.

It is not necessarily essential that the slots 20 be provided for the necessary freedom of movement for extensions 16 may be otherwise provided for. For example, as shown in Fig. 4, the cylindrical portion 17 may be offset forwardly from plate 11 to provide a clearance space 22 for the purpose described. Also the extensions need not necessarily be diametrically opposite to the hooks 10, but may be disposed with a somewhat forward inclination, as shown in Fig. 4 in connection with the extensions 16'.

Identifying marks or characters, such as numbers, may be associated with the extensions in any suitable way and may be applied directly to the extensions as shown in Fig. 5 or to some adjacent part, such as the plate 21, as shown in Fig. 3.

According to another feature of the invention, the extensions have an important function apart from that described and this function is accomplished whether or not the extensions pass outside slots 18. As shown in Fig. 6, the extension, such as 16², need not extend beyond the peripheral wall of the cylindrical portion 17. The provision of a hook having two portions which enter a slot 18 is important because of the double bearing thus afforded for guiding the hooks in their swinging movement. While this feature is of value in any key case, it is especially desirable in the so-called swivel hook key cases. The swivel heads usually have a rather loose fit within the hollow cylindrical member 17 and the hooks can move back and forth sideways to a considerable degree. The loose fitting heads naturally drop below the axis of member 17 and the degree of side play of the hooks is greater as the center of oscillation for the side play movement ap-

proaches the periphery of member 17. By providing two parts on the hook to ride in slot 18 and by locating these parts in more or less opposed relation, the degree of side play is not affected by the location of the center 70 of oscillation, wherever it may be, and the degree of side play is held within the desired limits, being those due to the necessary clearance between the hook and the side walls of its slot. Also an adequate guiding bearing is afforded for each hook. The thin circular wall of member 17 does not afford much of a bearing in the ordinary key case but when this thin wall is engaged by the hook at two substantially opposite points a 80 very substantial bearing is obtained.

While the swivel head of the hook may be constructed in any suitable way, according to the features of invention as above set forth, the invention is particularly applicable to the style of head illustrated in Figs. 7 and 8. As there shown, the upper end of the shank of hook 10 is bent into a substantially circular coil 23, the axis of which is substantially parallel with the shank of the 90 hook. The free end of the coil must naturally be bent inwardly inside the outer circumference of coil 23 in order not to catch on the edges of slot 18, when the hook turns about its own axis, or swivels. It is difficult to satisfactorily dispose of this rough ragged end, when the hooks are made in quantity production. With the present invention, this difficulty is overcome by carrying such end inwardly and then bending it 100 upwardly to form the extension 16².

The invention has been disclosed herein, in an embodiment at present preferred, with detailed variations, for illustrative purposes, but the scope of the invention is defined by 105 the appended claims rather than by the foregoing description.

What I claim is:

1. The combination with a key case, of a hollow cylindrical member connected thereto and provided with a series of longitudinally spaced and substantially transversely disposed slots in its periphery, and a series of key retaining devices one for each slot pivotally connected to said member for 110 swinging movement into and out of said case, the shank of each key retaining device extending through its slot to guide the device in its swinging movement, and a part 115 fixed to each device and extending through and beyond said slot to function as an auxiliary guide and as a selector.

2. The combination with a key case, of a hollow cylindrical member connected thereto and having a slot in its periphery disposed substantially transverse to the axis of 125 said cylinder, a key retaining member having a part engaged within said hollow member to support the key retaining member for 130 swinging movement into and out of the case,

the shank of said member depending from said part through said slot, the latter permitting the retaining member to swing throughout the desired range, and an extension from said part substantially opposed to said shank and extending into said slot to cooperate therewith as an auxiliary guide and restrict the side play of the key retaining member in the slot.

10 3. The combination with a key case, of a hollow cylindrical member connected thereto and having a slot in its periphery disposed substantially transverse to the axis of said cylinder, a key retaining member the shank of which enters said hollow member through said slot and is provided with a

substantially circular coil to form a swivel head, the latter disposed within the interior of said hollow member to support the retaining member for swinging movement 20 about an axis parallel to that of the hollow member and for swivelling movement about an axis substantially at right angles thereto, the end of said coil being bent outwardly and projecting therefrom on the opposite 25 side from said shank, said end entering said slot and cooperating therewith as an auxiliary guide to restrict the side play of the key retaining members in the slot.

In testimony whereof I have affixed my 30 signature.

HENRY CAVE.
